Primary Examiner — Cynthia R Underwood*(74) Attorney, Agent, or Firm* — Robert J. Myers**CLAIM**

I claim an ornamental design for a tie tail cut-off shield, as shown and described.

DESCRIPTION

FIG. 1 is a perspective view of the fifth embodiment of the tie tail cut-off shield;

FIG. 2 is a right side elevation view thereof;

FIG. 3 is a left side elevation view thereof;

FIG. 4 is a top plan view thereof;

FIG. 5 is a front elevation view thereof; and,

FIG. 6 is a back elevation view thereof; and the bottom of the tie tail cut-off shield is unornamented.

The broken lines are for the purpose of illustrating the environment of the article only and form no part of the claimed design. The shading illustrated in the drawings is provided merely to highlight the contour of the design and is not intended to be illustrative of any texture or gloss.
